UNITED STATES PATENT OFFICE.

LUCIUS C. PALMER, OF BALLSTON SPA, NEW YORK.

MACHINE FOR FORMING SCYTHES.

SPECIFICATION forming part of Letters Patent No. 299,675, dated June 3, 1884.

Application filed September 21, 1883. (No model.)

To all whom it may concern:

Be it known that I, LUCIUS C. PALMER, of Ballston Spa, in the county of Saratoga and State of New York, have invented a new and 5 Improved Machine for Forming Scythe, Corn-Knife, and Similar Blades, of which the following is a full, clear, and exact description.

My invention consists of arrangements of mechanism for swaging scythe, corn-knife, and 10 other like blades in uniform shape from back to edge, and true taper from heel to point, and so as to avoid the thick and thin places common in the blades made by plating with a hammer, the said mechanism being constructed 15 and arranged as hereinafter described.

Reference is to be had to the accompanying drawings, forming part of this specification, in which similar letters of reference indicate corresponding parts in all the figures.

20 Figure 1 is a side elevation of my improved swaging-machine with a part broken out. Fig. 2 is a plan view with a part in section. Figs. 3 and 4 are details of an eccentric device employed to shift the die on which the blades 25 are swaged to produce the taper of the blades from heel to point. Fig. 5 is a perspective view of the machine. Fig. 6 is a perspective view of the apparatus employed for adjusting the bed-die. Fig. 7 is a perspective view of 30 the oscillating die and the means for working it; and Figs. 8, 9, 10 and 11 are details of a clutch device employed for connecting the driving-gear and for working the shaping-dies for bending the blanks to produce the curve 35 from heel to point preparatory to rolling the same.

I use an oscillating die, *a*, and a bed-die or anvil, *b*, to roll the blades, and beginning at the heel I roll the blank crosswise from back 40 to edge, shifting the blank along on the bed-die by hand after each pass, and causing the bed-die to rise slightly at the same time and to advance toward the back gage, *l*, to reduce the blade in thickness from heel to point and 45 from edge to back. The oscillating die is suspended from a sliding block, *c*, by a pivot, *d*. The block is fitted in slideways *d'* in the under side of the cap *e*, and is connected by rod *f* with the crank *g* of the main shaft *h*. The 50 oscillating die *a* is also connected with the arm *i* of the rod *f* by a coiled spring, *j*, or it may

be any equivalent device. The said arm *i* projects downward from the end of rod *f* that is jointed to the slide *c*, so as to swing toward and from the die *a* by the vibrations of the rod *f*, caused by the crank, and the spring *j* is connected to the die *a*, near its lower end, so that said die will be made to swing forward and backward as the arm *i* swings. The object of this arrangement is to employ the spring to 60 throw the oscillating die forward and upward, as indicated in Fig. 7, to clear the blank when sliding back to the starting-point for the beginning of the passes, which it will be seen is effected by the downward movement of crank 65 *g* at the beginning of the back-stroke. Before the slide *c* arrives at the end of the back-stroke, but after the die has passed back over the blank, the lower end of the die *a* stops against a stud, *k*, where it is held until the 70 crank rises on the forward stroke. The use of this projection or stud *k* is as follows: It was found that the durability of the spring would be very much greater if some device could be made to extend the spring during 75 the backward movement of the oscillating die about one-half or one-fourth the amount that it was compressed in the forward movement of the die. The stop *k* was therefore placed on guide *l*, directly behind the bed-die *b*, and in the path of the oscillating die, for the rear edge of said die to bear against and extend the spring and cause the face of the die *a* to press upon the blank near to one side of said die when it commences its forward 85 movement. When this part of the oscillating die becomes worn, it may be reversed and the other side used, as it is made wide enough for this purpose, as will be readily seen from the drawings. The taper of the blade from back 90 to edge is produced by the rolling action of the upper die upon the lower, and by gradually lessening the distance between the two dies a taper from heel to toe is formed simultaneously with the taper from back to edge, 95 as will be fully understood from this specification, in connection with the drawings forming a part thereof. To raise the bed-die slightly after each pass of the oscillating die to produce the taper of the blade from heel to point, the bed-die *b* is secured on a die-block, 100 *m*, that is arranged on a wedge, *n*, up which

the die-block is to be shifted slightly each time the oscillating die makes a pass, the blank being also shifted lengthwise along the die. The wedge n is made adjustable by the rod 5 y^2 , nut z^2 , and bar x^2 to set it forward or backward, as may be required, for thicker or thinner blades. The block m is shifted by the eccentric o on a shaft, p , that is turned by a ratchet-wheel, q , pawl s , and lever t through the chain y , and the lever t is worked by the slide e , which strikes a screw, u , fixed on the lever, every time it moves back. The screw is employed for the point of contact of the slide with the lever, in order that it may be shifted to vary the extent of the movement of the block and the rise of the die. The pawl-lever t is pivoted at t' , or it may be on the ratchet-wheel stud v . The ratchet-wheel q is pivoted on a stud-pin, v , of the housing, and has a hub, w , to which a lever, x , attached to shaft p , is connected by a chain, y , for enabling said ratchet-wheel to turn the eccentric o , as above stated. The stud z , connecting the chain to the lever, 25 is adjustable along the slot a' of the lever to vary the movement of the eccentric and the rise of the die by that means also when required.

To shift the die-block m back again preparatory to swaging a new blank, another lever, b' , of shaft p is connected to a hub, c' , of a friction-wheel, d' , by a strap or chain, e' . Said friction-wheel is mounted on an eccentric, f' , which in turn is mounted on a stud, g' , of the housing, and connected by a stud, h' , with the lever i' , which, when pressed down by hand at the end of the long arm, will raise friction-wheel d' up into contact with shaft j' , by which the friction-wheel will be turned so as to shift 40 eccentric o and move the die-block back.

To raise the pawl s out of the teeth of ratchet-wheel q automatically, for allowing the eccentric o to be thus turned back, the pawl-lever t has a tripper, k' , pivoted at l' on an 45 arm, m' , of said lever, bent over said ratchet and down the side of it. This tripper is shifted under a stud, n' , of the pawl by a stud-pin, o' , set on the side of the ratchet-wheel, which strikes the tripper on its lower side above its pivot, thereby rocking it and causing its upper face to act with a cam-action on the stud-pin n' of the pawl, and raise said pawl out of engagement with the teeth of the ratchet-wheel. The stud-pin o' is adjustable on the 55 ratchet-wheel, and may be set for tripping the pawl earlier or later, according as the blades are long or short, and to throw back the tripper and allow the pawl to engage the ratchet again when the ratchet-wheel turns back.

60 Another stud-pin, p' , is set in the side of said ratchet-wheel to strike the tripper on the other side and shift it back from under the stud-pin n' of the pawl, to let the pawl fall into the teeth again.

65 For shaping the blanks to form the curves from heel to point preparatory to swaging them, I have arranged a stationary bending-

die, q' , on the plate s' , and a movable die, t' , on the slide u' , fixed in slotted ways v' , under plate s' , and connected by bar w' with the lever 70 x' . Said lever is worked by a cam, y' , on the part y^2 of a clutch keyed fast to the main shaft h . Said shaft remains at rest except when coupled to the continuously-running wheel z^2 by clutch z' , which coupling is effected at any 75 time when required by a spring in box a^2 whenever the lever b^2 is pulled down from between the two parts of the clutch, where it is kept by a spring, c^2 . Said lever b^2 has a tapered bit, d^2 , that wedges the two portions of 80 the clutch y^2 and z^2 apart. The spring f^2 , secured at one end to bar w' and at the other end to stationary plate f' , pulls back the die t' . The sliding part z' of the clutch carries pins x^2 , passing through part y^2 , and engaging both 85 notches in the side of wheel z^2 to cause the rotation of the crank-shaft h to set the cam y' and other parts of the machine in motion. The sliding part z' is also formed with an incline or cam-surface on its lower inner edge, 90 the said incline being widest at the forward edge and gradually tapered back toward the center. When the lever b^2 is released the incline b^4 will, during the revolution of the clutch, come in contact with the point of the 95 bit d^2 of lever b^2 , thereby causing this incline b^4 to ride over the inclined side of the bit toward its widest end and force the sliding part z' and its pins outward. The blank is placed between these dies $q' t'$, which then close on 100 and bend the blank to the required shape, after which it is placed on the bed-die to be rolled, said blank being gaged thereon by the curved gage l , fixed adjustably on the housings a suitable distance back of the bed-die b , 105 as shown relatively to said die in Fig. 6. This guide l is placed a suitable distance in rear of die b , and is curved approximately to the curve of the said die b . When this adjustment has been properly made, the heated 110 blank is shaped in the bending-dies $q' t'$, to be hereinafter described, and then placed upon the die b and against the guide l , and is held in this position by the operator. Besides bending the blank in these dies $q' t'$ before placing it under the die b , the slide u' is also made to operate a hammer-die, g^2 , which I call a "bunter," so as to press the rod against the face of the gage l at each back motion of slide u' and bend it to the shape of said die between 115 the passes of the roller-die to cause the rod to retain the shape given to it by the dies $q' t'$ and prevent it from being pressed out of shape by said roller-die.

The hammer-die g is attached to the upper 120 end of a lever, h^2 , pivoted to the side of the bed-frame near the bottom, and extending up past the slide u' , so that a shoulder of said slide will strike said lever and cause the die g^2 to strike the rod against the face of the gage 125 l or the end of an adjusting-screw, k^2 , of said gage. While the oscillating die is returning elevated over the blank the hammer-die g^2 strikes the blank close to said die, pressing

the blank against the curved guide *l*. At this moment the oscillating die *a* bites upon the blank, and the hammer *g*² is thrown back, and when the oscillating die has again operated 5 and is returning, the operator moves the blank a few inches, when the hammer-die *g*² again operates, causing the blank to retain the curvature given it by the bending-dies, and curving the small portion that was not shaped by 10 the bending-dies. This is continued until the blank is completed.

The work of this machine is superior to that produced by the plating-hammer, in that the plate is even from back to edge, and is true 15 in the taper from heel to point, there being no uneven or thick and thin places throughout the entire length, so that when the plate goes to the finishing-hammer, the dies of which are ground to cover a short section of the plate 20 from back to edge, said dies will act alike on the blade from heel to point as the blade shifts along between them by the jars of the machine, whereas a thick spot in the plate will prevent the finishing-hammer from properly hammering, refining, and condensing a thin spot 25 adjacent thereto, so that when such blades are heated for hardening and tempering they will not heat evenly, and the temper will be uneven. The blades produced by this machine being more even and uniform in thickness will finish with much less grinding than 30 the more uneven blades of the hammering process.

Having thus described my invention, what I 35 claim as new, and desire to secure by Letters Patent, is—

1. The combination, in a swaging-machine, of a reciprocating oscillating die with an adjustable bed-die, substantially as set forth.
2. The combination, in a swaging-machine, 40 of the oscillating die *a*, arranged on the reciprocating slide *c*, the bed or anvil die *b*, and a spring or analogous device for raising said oscillating die in its backward movement over the bed-die, substantially as set forth.
3. The combination, in a swaging-machine, 45 of the reciprocating oscillating die *a*, a bed-die, a spring or analogous device for causing the oscillating die to clear the bed-die in its backward movement, and a stop in the path of the oscillating die for arresting said die in its backward movement at a point over the blank for allowing said die to bite on the blank 50 in its forward movement, substantially as set forth.
4. The combination, in a swaging-machine, 55 of the oscillating die *a*, sliding block *c*, having said oscillating die pivoted on it, the arm *i*, connected to the vibrating rod *f*, and the spring *j*, connecting said oscillating die *a* and arm *i*, substantially as described.
5. In a swaging-machine having an oscillating die, *a*, pivoted to a reciprocating block, *c*, a die-block, *m*, mounted on an inclined bed, 60 *n*, and connected to an eccentric, *o*, having in-

termittent rotary motion to raise or shift die *b* toward die *a* during the intervals between the passes of said oscillating die *a*, substantially as described.

6. In a swaging-machine having an oscillating die, *a*, pivoted on a reciprocating slide, *c*, the die-block *m*, arranged on an inclined bed, *n*, and connected to eccentric *o* on a shaft, *p*, having an arm, *x*, connected by a chain, *y*, to the hub of a ratchet-wheel, *q*, having a pawl, 75 *s*, that is worked by the reciprocating slide *c*, substantially as described.

7. The tripper *k* on the pawl-lever *t*, in combination with pawl *s*, having stud *n'*, and with the stud-pins *o'* and *p'* of the ratchet-wheel *q*, substantially as described.

8. The friction-wheel *d'*, lever *i'*, drum *c'*, strap *e'*, arm *b'*, and shaft *j'*; in combination with the shaft *p*, having eccentric *o*, connected with die-block *m*, substantially as described.

9. The friction-wheel *d'*, lever *i'*, drum *c'*, strap *e'*, arm *b'*, and shaft *j'*, in combination with shaft *p*, having eccentric *o*, connected with die-block *m* and with the ratchet-wheel *q*, connected to said shaft *p*, and having the 90 tripper *k* to its pawl *s*, substantially as described.

10. In a swaging-machine, the stationary bending-die *q'*, movable bending-die *t'*, slide *u'*, connected thereto, pivoted lever *x'*, rod *w'*, 95 pivoted to the lower end of lever *x'* and to slide *u'*, and a cam, *y'*, for operating on the free end of the lever *x'*, substantially as shown and described.

11. In a swaging-machine, the combination 100 of the bending-dies *q'* *t'* and pivoted lever *x'*, connected to the movable die thereof, with the shaft *h*, gear-wheel *z'*, clutch mechanism *z'* *x'* *y'*, cam *y'*, and lever *b'*, provided with a wedge-tongue, *d'*, substantially as set forth.

12. In a swaging-machine, the gage *l*, in combination with the bed-die *b* and the oscillating die *a*, said oscillating die being arranged on a reciprocating slide, *c*, substantially as described.

13. In a swaging-machine, the bunter *g*², in combination with the gage *l*, bed-die *b*, and the oscillating die *a*, said oscillating die being arranged on the reciprocating slide *c*, and the bunter being operated by the slide *s'*, substantially as described.

14. The combination, in a swaging-machine, 115 of the bed-die *b*, the oscillating die *a*, arranged on the reciprocating slide *c*, arm *i* of the vibrating rod *f*, spring *j*, connecting said die to said arm, and the stud *k* of the gage *l* to stop the die *a* in the relation to die *b* for allowing said die *a* to bite on the blank in the forward movement of the said die, substantially as described.
